WALL OR FLOOR STRUCTURE AND SECUR-
ING MEANS

Le Roy B. Bachelder, Dayton, Ohio

Application September 18, 1936, Serial No. 101,447

12 Claims. (Cl. 72—19)

This invention relates to a wall or floor structure, and more particularly to a composite wall or floor comprising assembled sections, and includes the herein described method and means for securing and maintaining the sections in position.

In the following description, the wall or floor sections are described as comprising non-nailable material such as stone, marble, composition structures, argillaceous material, or the like. However, the method and means for fabricating a wall or floor structure is equally applicable to the other materials such, for example, as wood.

It is the general practice in fabricating walls or floor structures of marble, large tile, or the like, to provide a suitable backing such as wood lath or sheeting, apply plaster or mortar to the backing, and then set the marble or tile in the plaster or mortar which acts to some degree as a holding means. In fabricating a wall or floor of marble, or large tile, the blocks or slabs are additionally secured to the backing by means of wires secured in drilled or formed holes in the blocks or slabs and then to the backing. Such procedure has required the services of skilled workmen, and has thus substantially increased the cost of installation. Additionally, the means heretofore used for securing the blocks or slabs to the backing has not been sufficiently positive to prevent the blocks or slabs from becoming loosened from the backing, particularly where the position of the backing shifts slightly due to building settling or changes in weather conditions.

One object of this invention is to provide a wall or floor structure which is simple and inexpensive to install and is so secured to the backing that it will be permanent regardless of changes in the position of the backing due to the building settling or weather conditions, together with a method and means for fabricating such wall or floor structure.

Another object of the invention is to provide a wall or floor structure which can be installed by unskilled workmen.

Still another object of this invention is to provide a wall or floor structure held in place by positive securing means and wherein the securing means does not show at the outer face of the wall or floor structure.

A further object of this invention is to provide a wall or floor structure and securing means therefor which will lend itself to easy removal of the wall structure when such removal is desired.

A still further object of this invention is to provide a wall or floor structure which may be fabri-

cated without the use of plaster or mortar as a part of the backing.

A still further object of this invention is to provide a wall or floor structure which when fabricated will be waterproof.

With the above primary and other incidental objects in view, as will more fully appear in the specification, the invention consists of the features of construction, the parts and combination thereof, and the mode of assembly, or their equivalents, as hereinafter described and set forth in the claims.

Referring to the accompanying drawing, wherein is shown the preferred but obviously not necessarily the only form of embodiment of the invention,

Fig. 1 is a perspective view showing a plurality of slabs or blocks constructed in accordance with the idea disclosed by this invention, and in the relative positions which they would occupy in the fabrication of a wall or floor structure.

Fig. 2 is an enlarged detail view showing the means and the method of securing a block or slab to a suitable backing.

Fig. 3 is a perspective view of the rearward or back side of a slab or block which is disposed against the backing when the wall or floor structure is assembled.

Fig. 4 is a fragmentary detailed view illustrating the use of mortar or plaster at the joint between the blocks or slabs.

Fig. 5 is a side elevation, partly in section, showing a corner block, wainscoting and floor assembly.

Fig. 6 is a sectional view showing a wainscot- 35 ing and cap mold assembly.

Fig. 7 is a side elevation of a modified form of securing means for the blocks or slabs to a backing.

Fig. 8 is a perspective view of the preferred 40 form of means for securing the blocks or slabs to a backing.

Figs. 9, 10, 11, and 12 are views showing various modifications of the means for securing blocks or slabs to a backing.

Like parts are indicated by similar characters of reference throughout the several views.

Referring to the drawing, and particularly Fig. 1 thereon, there is shown a plurality of blocks or slabs 1, which may be of marble, synthetic marble, tile, or the like, constructed in accordance with the idea disclosed by this invention and assembled together as they would normally be to form a wall or floor structure. Each slab or block 1 is provided with a groove 2 on its marginal sur-

55

faces, that is, along the length and width of each block, and the blocks are shown as being disposed in what is known as broken joint, or ashler relation, although any preferred arrangement 5 may be used.

A fastening device for holding the blocks in position preferably takes the form of an enlarged head nail which includes a stem or shank portion 3 adapted to be driven into sheathing 4 or studding 5, Fig. 5, and also includes a head portion 6 which is shaped to be complementary to the groove 2 in the marginal surfaces of each block 1. As shown in Fig. 3, the head portion 6 of the fastening device, is elongated and extends 10 a substantial distance along the groove 2, the purpose of this elongated head being to provide a greater area of gripping action between the head portion 6 of the fastening device and the block.

Referring to Figs. 7, 9, and 10 it will be seen 20 that the head portion 6 of the fastening device may take various forms, for example, a ball-like shape as shown in Figs. 7 and 9, or a relatively sharp angular shape as is shown in Fig. 10. In the use of a fastening means having a head portion 25 shaped as in Fig. 10, it will be understood that the groove 2 in the marginal surfaces of each block 1 is shaped so that the head of the fastening device and the groove will be complementary.

In the method of assembling a wall or floor 30 structure in accordance with this invention, and with the use of the fastening means herein disclosed, a sheathing 4 of any desired thickness is preferably applied to studding 5 to provide a backing for the slabs or blocks 1, although studding may be arranged to correspond to the position 35 of the block or slab assembly joints if desired. Next, a slab or block is properly positioned against the backing and a fastening device is driven into the backing at an angle to the plane of the front 40 and back sides of the slab or block, and in such manner that a portion of the stem or shank 3 of the fastening device will lie within the area defined by the slab or block. Such fastening device is driven into the backing until the head 45 portion 6 thereof is in substantial alignment with the groove 2 in the marginal surface of the block, and the stem or shank of the fastening device is then bent as illustrated in Figs. 2 and 5 until the head 6 of the fastening device enters the groove 2, thus serving to hold the block or slab 1 in position 50 against the backing. As many of these fastening devices may be used as desired, and at as many sides of the slab or block 1 as found necessary.

Following the securing of the first block or slab 1 to the backing in the manner just described, another block or slab is placed against the backing in edge to edge relation with the first block. If desired, plaster or mortar 7 may be 55 wiped into the groove 2 of the blocks. The second block or slab 1 is then moved toward the first block or slab which has been attached to the backing until the remainder of the head 6 of the fastening device disposed in groove 2 of the first block or slab enters the groove 2 of the second block or slab, the second block being then further secured to the backing at its other marginal surfaces by the use of a desired 60 number of fastening devices driven into the backing in the manner previously described. It is preferable that there be sufficient plaster or 65 mortar wiped into the grooves 2 so that the plaster or mortar will be extruded by movement of two blocks into juxtaposition to thus provide a sealed 70 joint between adjacent blocks or slabs.

By the use of the method of assembly and fastening device as just described it will be apparent that no part of the fastening device will appear at the outer surface of the wall or floor structure. As shown in Fig. 3, the marginal surface 75 between the grooves 2 of the blocks or slabs and the rearwardmost face of the blocks or slabs is cut away as at 8 to accommodate the stem or shank 3 of the fastening device whereby the blocks or slabs may be moved as closely adjacent 10 one another as is possible while still providing a plaster or mortar joint between adjacent blocks or slabs. These cutout portions 8 may be formed in any desired manner such, for example, by chipping out small portions of the blocks or slabs or 15 by forming the cut-out portions during the molding process where a molded block or slab is employed to make the wall or floor structure.

Referring to Fig. 6, a block or slab 1 is shown 20 which is particularly adapted for use adjacent the point of jointure between the side walls, floor and ceiling of a room wherein a wall or floor structure as herein disclosed is employed. It will be noted that the slab or block is mitered at the corners of the room as indicated at 9 to provide a horizontal portion 10 and a vertical portion 11, and is arranged to eliminate any joint between blocks directly at the room corners. After this particularly shaped block or slab 1 is positioned and properly secured by the fastening 25 device as shown in Fig. 5, other blocks or slabs 1 may be assembled in adjacent or abutting relation with the exposed marginal surfaces of such shaped block or slab to provide a wall or a floor structure.

In Fig. 6 of the drawing, there is shown the combination of a wainscoting 12, a cap mold 13, and plaster 14, combined in a wall structure. The wainscoting 12 and cap mold 13 are secured to the backing by a fastening device such as 40 hereinbefore described.

Provision has been made for securing slabs or blocks to the backing which consists of, for example, metal lath. Such a fastening device is shown in Fig. 7 wherein the stem or shank 3 of 45 the fastening device is curved as at 15 to form a hook which may be engaged in the lath or backing with the head portion 6 of the fastening device in a position to rest in the grooves 2 of the slabs or blocks 1. In Fig. 14 the stem or shank 3 of the 50 fastening device takes the form of a screw, such fastening device being used in the same manner as the fastening device wherein the stem or shank takes the form of a smooth nail.

Referring to Fig. 12 a fastening device is shown 55 which is particularly adapted to use at the marginal surface of a block or slab which abuts a wall at the corner of a room. It will be noted that one side of this fastening device is made flat as at 60 60, while the remainder of the head of the fastening device is of a convolution to be complementary to the groove 2 in the blocks or slabs 1. In the use of this type of fastening device, the fastening device is driven or secured to the backing with the flat side adjacent the wall perpendicular 65 to that on which the blocks or slabs are being assembled with a block or slab being moved toward the perpendicular wall to receive the portion of the head complementary to the groove.

From the above description it will be apparent 70 that there is thus provided a device of the character described possessing the particular features of advantage before enumerated as desirable, but which obviously is susceptible of modification in its form, proportions, detail construction and ar- 75

angement of parts without departing from the principle involved or sacrificing any of its advantages.

While in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. The method of assembling a wall or floor structure, made up of slabs of material having recesses in their marginal faces intermediate the front and back planes of the slab, with a fastening means having a shank and a head complementary to the recesses in the marginal faces of the slabs which comprises positioning a slab against a suitable backing, driving the shank of the fastening means into the backing until the head of the fastening means is in substantial alignment with a recess in the marginal face of the slab, and then bending the shank of the fastening means until a portion of the head thereof is disposed in the recess.

2. The method of assembling a wall or floor structure, made up of slabs of material having recesses in their marginal faces intermediate the front and back planes of the slab, with a fastening means having a shank and a head complementary to the recesses in the marginal faces of the slabs which comprises positioning a slab against a suitable backing, driving the shank of the fastening means into the backing at an angle such that a portion of the shank thereof will ultimately lie within the area defined by the slab and until the head of the fastening means is in substantial alignment with a recess in the marginal face of the slab, and then bending the shank of the fastening means until a portion of the head thereof is disposed in the recess.

3. The method of assembling a wall or floor structure, made up of slabs of material having recesses in their marginal faces intermediate the front and back planes of the slab, with a fastening means having a shank and a head complementary to the recesses in the marginal faces of the slabs which comprises positioning a slab against a suitable backing, driving the shank of the fastening means into the backing until the head of the fastening means is in substantial alignment with a recess in the marginal face of the slab, and then bending the shank of the fastening means until a portion of the head thereof is disposed in the recess, placing another slab against the backing, and moving it into juxtaposition with the first mentioned slab and until the remainder of the head of the fastening means enters a recess in the marginal surface thereof coincident with the marginal surface of the first slab.

4. A wall or floor structure comprising a backing and blocks adapted to be disposed in edge to edge relation on the backing, coincident recesses in the marginal surfaces of the blocks, and means for securing the assembled blocks to the backing including a fastening device engageable with the backing and having a head of a shape substantially corresponding to the contour of the recesses in the marginal surfaces of the assembled blocks and engaging the recesses through-

out their width transversely of the blocks when disposed therein.

5. A wall or floor structure comprising a backing and blocks adapted to be assembled in edge to edge relation on the backing, coincident 5 grooves in the marginal surfaces of the blocks, and means for securing a block to the backing including a fastening device engageable with the backing and having a head of a shape substantially corresponding to the contour of the grooves 10 in the marginal surfaces of the blocks and engaging the recesses throughout their width transversely of the blocks when disposed therein.

6. A wall or floor structure comprising a backing and a block adapted to be disposed on the 15 backing, a groove in the marginal surfaces of the block, and means for securing the block to the backing including a fastening means engageable with the backing and having a head portion of a shape substantially corresponding to the contour of the grooves in the marginal surfaces of the block and engaging the recesses throughout 20 their width transversely of the blocks when disposed therein.

7. A wall or floor structure comprising a backing and blocks adapted to be assembled on the backing, grooves in the marginal surfaces of the blocks, and means for securing the blocks to the backing including a fastening means having a 25 shank engageable with the backing and an elongated head portion having a shape substantially corresponding to the contour of the grooves in the marginal surfaces of the blocks and extending along the length of the grooves, said head portion being such as to engage the grooves 30 throughout their width transversely of the blocks when engaged therein.

8. The method of assembling a wall or floor structure made up of individual blocks having grooves in their marginal surfaces and securing 40 the blocks in assembled relation with a fastening device having a shank and a head portion complementary to the grooves in the blocks, which comprises positioning a block on a suitable backing, driving the shank of the fastening device 45 into the backing at an angle to a plane perpendicular to the front and back surfaces of the block, and then bending the shank of the fastening device until the head portion thereof fits within the groove.

9. The method of assembling a wall or floor structure made up of individual blocks having grooves in their marginal surfaces and securing the blocks in assembled relation with a fastening device having a shank and a head portion complementary to the grooves in the blocks, which 55 comprises positioning a block on a suitable backing, driving the shank of the fastening device into the backing at an angle to a plane perpendicular to the front and back surfaces of the block, and 60 then bending the shank of the fastening device until the head portion thereof fits within the groove positioning another block beside the first block and moving it toward the first block until the head of the fastening device fits within the 65 groove of the second block as it does in the groove of the first block.

10. The method of assembling a wall or floor structure made up of individual blocks having grooves in their marginal surfaces and securing 70 the blocks in assembled relation with a fastening device having a shank and a head portion complementary to the grooves in the blocks, which comprises positioning a block on a suitable backing, driving the shank of the fastening device 75

into the backing at an angle to a plane perpendicular to the front and back surfaces of the block, and then bending the shank of the fastening device until the head portion thereof fits 5 within the groove, positioning another block beside the first block, filling the grooves in the blocks with a mortar, and moving the second block toward the first block until the head of the fastening device fits within the groove of the 10 second block as it does in the groove in the first block, sufficient mortar being extruded to completely fill any space between adjacent edges of the blocks.

11. A wall or floor structure comprising a backing 15 and a block adapted to be disposed on the backing, a groove in the marginal surface of the block, and means for securing the block to the backing including a fastening means having a shank engageable with the backing and a head portion integral therewith and of a shape substantially corresponding to the contour of the 20 groove in the marginal surface of the block and

engaging the groove throughout the width thereof or transversely of the block when engaged therein.

12. A wall or floor structure for a room wherein the walls and floor are disposed perpendicular to each other, comprising backings arranged to define the shape of the room, blocks adapted to be disposed on the backings to form the inner surface of the room, grooves in the marginal surfaces of the blocks and means for securing 10 the blocks to the backings adjacent the point of jointure of the perpendicular backings, including a fastening means having a shank engageable with a backing and a head portion shaped to correspond substantially to the contour of the groove and to coincide with the surface of the adjacent perpendicular backing, said head portion being such as to engage the grooves throughout their width transversely of the blocks when engaged 15 therein. 20

LE ROY B. BACHELDER.
